Des. 210,168
Patented Feb. 13, 1968

210,168

JAR CAP

Carl M. Plochman, Jr., Chicago, Ill., assignor to Plochman, Inc., Chicago, Ill., a corporation of Illinois

Filed Apr. 17, 1967, Ser. No. 6,724

Term of patent 14 years

(Cl. D58—26)

FIGURE 1 is a perspective view of a jar cap showing my new design, the broken line showing of a jar being for illustrative purposes only;

FIG. 2 is a top plan view;

FIG. 3 is a side elevational view;

FIG. 4 is an enlarged scale sectional view taken on line 4—4 of FIG. 2;

FIG. 5 is an enlarged scale sectional view taken on line 5—5 of FIG. 2; and

FIG. 6 is an enlarged scale fragmentary top plan view.

I claim:

The ornamental design for a jar cap, as shown and described.
